UNITED STATES PATENT OFFICE.

JAMES MENZIES, OF FERNANDINA, FLORIDA.

SEAL-LOCK.

SPECIFICATION forming part of Letters Patent No. 280,649, dated July 3, 1883.
Application filed March 24, 1883. (Model.)

To all whom it may concern:

Be it known that I, JAMES MENZIES, a citizen of Great Britain, residing at Fernandina, in the county of Nassau and State of Florida, have invented a new and Improved Seal-Lock, of which the following is a specification.

My invention relates to that class of locks which are adapted to be sealed by having their key-holes in some manner covered or made 10 inaccessible, so that the key cannot be inserted without leaving evidence of the fact, and its object is to provide a simple device which may be attached to padlocks now in use on railway-cars or elsewhere, or they may be made 15 as a portion of new locks, to so guard the key-hole that the key cannot be inserted after the guard is applied without leaving evidence of such act.

To this end it consists in the construction 20 and combination of parts forming a seal-lock hereinafter described and claimed, reference being had to the accompanying drawings, in which—

Figure 1 is a front elevation of a lock having my invention attached, and showing the 25 same as locked and sealed. Fig. 2 is an edge view of the lock, showing the seal-holding device in vertical section.

A represents the body of a padlock, the key-hole *a* being shown in dotted lines as covered by other parts.

B represents the frame of my attachment, secured to the face of the lock by means of screws or rivets, which may be concealed by 35 any usual method or cast on the body of the lock at time of manufacture. This frame is open, like a window, in front of the key-hole *a*, and is provided with grooves in its two sides behind the front frame, C, in which to insert a 40 pane of glass, D, which I call the "seal." The side grooves, *c*, are connected by a groove across the bottom to receive the lower edge of the seal. Directly under the seal, and plainly visible through it, is a card or paper, *d*, on 45 which is printed any desired heading—such as "L. and N. R. R."—and any private marks understood by the sender and the receiver—such as the number "168" or as the name "Louisville, Kentucky." This card or paper may be in any 50 manner stuck to the back of the glass seal. Behind the card or paper *d* is a hinged lid, *e*, covering the key-hole. The seal is kept in place by an arm, *E*, secured to the pivot *f* of

the lock-shackle *F*, the lower extremity of arm *E* resting on the upper edge of the seal-glass *D*. The shackle *F* is rigidly fixed to its pivot *f* to turn therewith, and when the lock is open the shackle *F* and its lower arm, *E*, are thrown over back, the arm *E* being out of the way, so that the seal may be readily inserted and the shackle may be hooked into the staple.

G is a guard, like the usual key-hole guard, pivoted to swing across the opening in frame *B* to protect the seal-glass, and *g* is a spring- 6 catch to keep the guard in place.

The method of use is as follows: The sender marks the card or paper *d* as agreed upon between him and the receiver, shuts down the lid *e*, slides the seal, with the marked card attached, into grooves *c*. Then, after closing the car-door and arranging its hasp, he hooks shackle *F* into the staple and shuts it into the lock, which, having a spring-bolt, holds it, and by means of arm *E* it also holds the seal *D* in 7: its frame. In this condition there is no possible way of getting at the lock to unlock it without first breaking the seal. When the car reaches its destination and the receiver wishes to open it, he must first break the seal-glass, then raise the lid which is placed over the key-hole to keep bits of glass from entering the lock. Then he may apply the key and unlock it. Each road over which the car passes will be held responsible to see that the 8c seal is unbroken and that the number or mark on the card accords with the way-bill, so that any robbery or peculation can be located and charged to the defaulting road.

What I claim as my invention; and wish to 90 secure by Letters Patent, is—

The combination, with a spring-padlock, *A*, having its shackle pivot-pin *f* secured to the shackle *F*, to swing therewith, of an arm, *E*, secured to said pin, a grooved frame, *B*, secured 95 to the face of the lock to receive a glass seal, *D*, or other breakable cover for the key-hole, said arm *E* covering the entrance to said grooved frame when the shackle is locked down to prevent the removal of said seal, substantially as and for the purpose specified.

JAMES MENZIES.
